UNITED STATES PATENT OFFICE

WILLIAM H. FURNESS, OF NATIONAL PARK, NEW JERSEY, ASSIGNOR TO CELLOCILK COMPANY, OF PHILADELPHIA, PENNSYLVANIA, A CORPORATION OF DELAWARE

APPARATUS FOR WINDING ARTIFICIAL SILK THREAD

Original application filed April 6, 1927, Serial No. 181,614. Divided and this application filed December 12, 1927. Serial No. 239,403.

This invention relates to method of and apparatus for winding artificial silk thread, and it is an improvement upon the method and apparatus shown in my United States 5 Patent No. 1,338,648, issued April 27, 1920.

One of the primary objects of my invention is to make it possible to wind fine filament artificial silk thread, preferably while imparting twist to it, on a spool or bobbin 10 by a cap. Heretofore it has been impossible to do this with fine filament silk thread because of the injury done to the thread in so winding it. In the practice of my invention I do not injure the thread.

15 More broadly, it is an object of the invention to wind artificial silk thread, whether of fine or coarse filament, on a spool with the employment of a cap without physical injury to the thread.

20 It is another object of the invention to provide cap twister mechanism which is simple, compact and certain in its operation, and in which the means for securing relative reciprocation of the spool and cap is very much 25 simplified.

I obtain the foregoing, together with such other objects and advantages as may herein-after appear, or are incident to my invention, by means of a method and apparatus illus- 30 trated in the accompanying drawings, of which—

Fig. 1 is a front elevation of a spindle suitable for the practice of my invention.

Fig. 2 is a sectional view of the cap twister 35 mechanism drawn on an enlarged scale.

Fig. 3 is a still further enlarged sectional view of certain parts of the twister mechanism.

Fig. 4 is a section taken on the line 4—4 of 40 Fig. 2 on an enlarged scale.

Fig. 5 is a section through a detail of the cap twister mechanism, the section being taken on the line 5—5 of Fig. 3, and

45 Figs. 6 and 7 are somewhat diagrammatic views illustrating what occurs as the thread is being wound.

Referring now to Fig. 1, the reference character A denotes the "spindle" as a whole. Certain parts of the spindle do not constitute 50 any part of the present invention, but are

shown, described and claimed in my copending application, Serial No. 239,401, filed Dec. 12, 1927.

It will suffice for the purposes of this specification to point out that the solution (preferably a copper-hydrate-ammonia-cellulose solution) is discharged into the bath 7 through the medium of a spinneret and suitable extrusion pump. The filaments converge to form the thread 8, such thread being drawn over the drawing mechanism *a* from which it is led to the cap twister mechanism *b* which forms a part of the present invention. Suitable guides 9 are provided for the thread where needed. 65

A driving unit *c* is provided for operating the extrusion pump, the drawing mechanism and the cap twister mechanism, such driving mechanism constituting no part of the present invention, the same being shown, described and claimed in my copending application Serial No. 239,402, filed Dec. 12, 1927. 70

The cap twister mechanism *b* comprises the cap 10 which is detachably carried on the top of the spindle 11; the spool 12 which is detachably supported on the spindle 13 which is hollow and houses the spindle 11; and the pulleys 14 and 15 which, respectively, drive the spindles 11 and 13. 75

The pulleys 14 and 15 are driven from the driving unit *c* by means of a belt not shown, the diameter of the pulley 14 being larger than that of the pulley 15, in consequence whereof the spool 12 rotates more rapidly than does the cap 10 for reasons 80 which will appear hereinafter.

I avail myself of the difference in speed of rotation of the two spindles to provide a very simple arrangement for imparting reciprocatory movement to the spool. The spindle 11 is provided with crossing threads 16 for a portion of its length and mounted thereon is a sleeve member 17 which is provided with a shoe 18 which engages the thread. The sleeve 17 is trunnioned in the block 19 by means of the two pins 19*a*. The opening in the sleeve is such that the sleeve can tilt or rock on the axis of rotation of the pins 19*a*. The pins 19*a* project through slots 20 formed in the spindle 13. Consequently, 100

owing to this arrangement and the difference in speed of the two spindles, the shoe 18 and, therefore, the sleeve will be moved longitudinally of the spindle 11, and will tilt when 5 the shoe reaches either end of one of the threads of the spindle 11, and thus the shoe will enter the other crossing thread. For example, when the shoe 18 reaches the top of the threaded portion, it will tilt and then 10 move downwardly to the end of the threaded portion when it will again tilt and then move upwardly. Since the spool 12 rests upon the block 19, it moves upwardly and downwardly with the sleeve 17.

15 In order to make the reversing shoe positive and certain in its operation, I so shape the opening in the sleeve 17 that it can tilt only on the axis of the pins 19a. To this end there is only a slight clearance between the 20 sleeve 17 and the threaded portion of the stem at the points marked 21 in Fig. 4. The clearance shown in the drawings is somewhat exaggerated. Fig. 5 is a cross section of the sleeve taken in a plane at right angles to 25 the plane in which the pins 19a extend, and illustrates the clearance which permits the rocking of the sleeve on the axis of the pins 19a.

It will be seen that the foregoing arrangement is simple and compact and certain in 30 operation.

Referring, now, to the manner in which the thread is twisted and laid upon the spool by the mechanism described, it will be observed that the thread is laid on the spool 35 with the employment of a loop or balloon 22 and is twisted.

The rate of feed of the thread and the rate of rotation of the spool determine the rate of 40 rotation of the loop. As the diameter of the spool increases as the thread is wound, the rate of rotation of the loop increases somewhat, with the net result that the thread is wound at an approximately constant rate. 45 When the spool is started, the thread moves across the lip of the cap at a steep angle as shown in Fig. 6. If, now, the cap be caused to rotate at the speed at which the loop rotates when the spool is started, the only relative movement as between the cap and the thread will be the inward movement of the thread with the rubbing in the direction of the fibres of the thread, that is to say the cap will not rub across the thread. This 55 latter rubbing damages the thread.

I prefer to operate the cap at a constant speed the same as that of the loop when a new spool is started, the spool also being operated at constant speed.

60 As the speed of the loop increases with increase in diameter of the spool, there is some movement of the cap across the thread, but the angle of movement of the thread changes, becoming flatter and flatter, as shown in Fig. 7, and hence the rubbing of

the thread on the cap is still in a direction generally longitudinally of the thread.

I have found that by so operating it is not necessary to dress the lip of the cap with wax or other substance calculated to protect 70 the thread, and that fine filament thread can be twisted without damage or breakage.

By operating at constant speeds the apparatus is much simplified.

The drawing mechanism is designed to impart stretch to the formed thread to the extent that the loop would stretch the thread when the loop has its greatest centrifugal force. Hence, no appreciable stretching occurs in winding. However, the thread is 80 laid up under light tension which prevents tangling.

This is a division of my copending application, Serial No. 181,614, filed April 6, 1927.

I claim:—

1. In cap twister mechanism, a cap, a cap spindle having crossing threads, a spool, a hollow spool spindle surrounding the cap spindle, a reversing nut on the cap spindle 90 adapted to transmit reciprocatory movement to the spool, said nut being non-rotatively associated with the spool spindle, and means for operating the spindles at different speeds.

2. In cap twister mechanism, a cap, a cap spindle having crossing threads, a spool, a hollow spool spindle surrounding the cap spindle, a reversing nut on the cap spindle adapted to transmit reciprocatory movement to the spool, said nut being non-rotatively associated with the spool spindle, and means for operating the spindles at different speeds, the nut comprising a tilting sleeve with a thread engaging portion; with the opening in the sleeve of such configuration that it can tilt only on the axis which permits reversal.

3. In cap twister mechanism, a cap, a cap spindle having crossing threads, a spool, a hollow spool spindle surrounding the cap spindle, a block adapted to support the spool, a reversing nut on the cap spindle trunnioned in the block and non-rotatively associated with the spool spindle, and means for operating the spindles at different speeds.

In testimony whereof I have hereunto signed my name.

WILLIAM H. FURNESS.
